ILLUMINATED ORNAMENT

Earl A. Miller, Orem, Utah 84057

Filed Jan. 25, 1971, Ser. No. 109,722

Term of patent 14 years

Int. Cl. D26—03

U.S. Cl. D48—20

FIG. 1

FIG. 6

FIG. 2

FIG.5

FIG. 1 is a side elevation view of an illuminated ornament embodying my new design;

FIG. 2 is a top plan view thereof;

FIG. 3 is an elevation taken from one end thereof.

FIG. 4 is an elevation taken from the end opposite that shown in FIG. 3;

FIG. 5 is a bottom plan view thereof; and

FIG. 6 is a fragmentary cross sectional view taken on line 6—6 of FIG. 1.

I claim:

The ornamental design for an illuminated ornament, as shown.
